UNITED STATES PATENT OFFICE.

IRVIN RITTENHOUSE, OF WASHINGTON, DISTRICT OF COLUMBIA, ASSIGNOR TO
HORACE F. CLARK, OF WASHINGTON, DISTRICT OF COLUMBIA.

PAPER-FASTENER.

1,149,086.

Specification of Letters Patent.

Patented Aug. 3, 1915.

Original application filed March 10, 1910, Serial No. 548,339. Divided and this application filed April 28, 1913, Serial No. 764,169.

To all whom it may concern:

Be it known that I, IRVIN RITTENHOUSE, a citizen of the United States, residing at Washington, in the District of Columbia, have invented new and useful Improvements 5 in Paper-Fasteners, of which the following is a specification.

This invention relates to improvements in paper fasteners, and more particularly to a 10 type of paper fastener that may be properly designated a flat file fastener, and is a divisional application of my pending application, Serial Number 548,339.

The object of this invention is to provide 15 a fastener which will securely bind together a stack of papers for the purpose of filing, a fastener of such a character to be particularly adapted for use in vertical filing systems wherein economy of space is an important item.

The invention disclosed herein resides in the construction, arrangement and combination of parts hereinafter described in a preferred form, reference now being made to 25 the drawing, in which:

Figure 1 is a top plan view of the base member showing a fastening pin inserted therethrough; Fig. 2 is a side elevation of Fig. 1; Fig. 3 is a section on the line 3—3 30 of Fig. 1; and Fig. 4 is a view partly in section, showing the complete fastener binding a stack of papers.

As shown in the drawings, 1, represents the base member which is formed of an 35 elongated strip of sheet metal having a main body portion 2, and end portions 3 and 4, struck-up from the main body portion, and lying in the plane parallel with, and slightly above the said main body portion.

40 5, is a central struck-up portion lying in the same plane as the struck-up end portions.

The angular portion between the several struck-up portions and the main body of the 45 base member are provided with a plurality of openings 6, 7, 8, and 9, which openings are in longitudinal alinement to permit the insertion of the flexible fastening strip 10. The fastening strip 10 is of a length considerably greater than the base member, to provide, upon its insertion into the same, 50 portions 11 and 12, extending away from the opposite edges of the base member, the

function of which will be hereinafter more fully described.

As shown, the base member is designed to engage the lowermost sheet of the papers desired to be secured by the fastener. On the uppermost sheet, is provided a protecting binding member 13, of a length somewhat greater than the length of the base member and having apertures 14 and 15 spaced apart a distance corresponding to the length of the said base member. To increase the transverse tensile strength of the protecting plate, and also to provide offsets at the points 14 and 15, whereby the extensions of the fastening pin may be readily inserted into the apertures, the portion between the said apertures is struck-up to lie 70 in a plane slightly above the plane of the protecting plate. The advantages of this form of construction having been fully set forth in my co-pending application, Serial Number 758,283.

75 The operation of the device is as follows: The flexible fastening strip 10 is inserted into the base member 1, by passing it through the series of openings 6, 7, 8, and 9, until the extensions 11 and 12 are of distances substantially equal from the opposite edges of the base member. These extensions are then bent upwardly over the said edges, until they are in vertical position to form piercing prongs for the securing of 85 the papers, which are pierced one by one, by the prongs as the file is built. If desired, the papers may be punched in any suitable manner, previous to their insertion on the fastener, in which case, a large number 90 of papers may be passed over the prongs in one operation. When the desired number have been placed in their position on the fastener, the protecting plate is slipped on the uppermost sheet and the ends of the 95 prongs, into the apertures 14 and 15 thereon, and the ends of the said prongs are then bent downwardly and outwardly, until they come into intimate contact with the papers.

100 The advantage of constructing the base member in the form illustrated in this application is that, in addition to the struck up end portions, a central portion is brought into direct contact with the surface of the papers, whereby a binding action of the 105 fastener is obtained at three points, instead

of only two, as has been heretofore shown in my Patent No. 920,393. This obviates the springing outward of the base member at the center from the surface of the bottom-most sheet, while the free ends of the fastening strip are being bent back and forth during the operation of securing additional sheets of papers into the file or removing sheets therefrom. In addition, the papers are more securely bound by the fastener than could be otherwise obtained, thus effecting a very flat file, a result most desirable to those who appreciate the value of economy of space in vertical filing systems.

15 What is claimed is:

A paper fastener comprising a base member having struck-up end portions and a

struck-up central portion, the surfaces of the struck-up portions lying in a plane parallel with the base, angular portions connecting the struck up portions, the angular connecting portions having perforations, and a pliable fastening strip inserted through the perforations under the struck-up portions and over the base portion adapted to be bent up over the struck-up end portions. 20 25

In testimony whereof I have hereunto set my hand in presence of two subscribing witnesses.

IRVIN RITTENHOUSE.
